TIME SWITCH

Arthur F. Geisel, Milwaukee, Wis., assignor to
 Perfex Corporation, Milwaukee, Wis., a corpora-
 tion of Wisconsin

Application April 17, 1946, Serial No. 662,803

2 Claims. (Cl. 161—1)

1

This invention relates generally to time switch mechanisms and more particularly to a time switch mechanism permitting manual actuation of the switch mechanism independently of the timing interval.

The primary object of the present invention is to provide an improved time switch device in which it is possible to actuate the switch mechanism manually without interfering with the normal clock actuated operation of the switching mechanism. A further object of the invention is to provide a time switch with a manual operating device which is easily accessible and operable without removal of the cover of the time switch mechanism.

Other objects and advantages of the invention will be hereinafter described and particularly pointed out in the claims.

In the drawings:

Fig. 1 is a perspective view of the timer with the front cover removed,

Fig. 2 is an enlarged perspective view of the manual operating mechanism, including a sectional portion of the front cover on which the manual operating mechanism is mounted,

Fig. 3 is a perspective view showing the outer appearance of a timer embodying the feature of the invention.

While I have illustrated and will herein describe but a single embodiment of the present invention, it will be understood that various modifications and alternative arrangements may be made by those skilled in the art without departing from the spirit and scope of the invention as defined by the appended claims.

In the form disclosed herein, the invention is an improvement in a 24 hour timer of a type described in detail in the Malone Patent 2,288,636, issued July 7, 1942. This device is adapted to be mounted on a wall or other suitable support and includes a mounting base 10 to which is fitted a separate casing box 11 to form an enclosure or chamber within which the operating elements of the mechanism are housed. Generally, the operating mechanism of the timer comprises a synchronous motor 12 mounted on the bracket 24 and adapted to actuate a switch mechanism. This switch mechanism is mounted on the base 10 and is electrically connected to the means to be controlled through terminals 13. The side portions of the base piece each contain knock-out openings 14 and 15, through which the desired connecting wiring may pass. The cover has its side walls slotted, as at 16, to clear the openings provided in the base.

In the timer the switching mechanism (not shown) is of such a character that it is shifted between two positions by the synchronous motor and after it has been shifted from one position to the other, it will maintain its new position until an opposite shifting movement is imparted to it. For details of this switching mechanism, reference may be had to the Malone Patent 2,288,636. The switching structure is protected by an L-shaped insulating cover structure 17 which is secured to the mounting plate 18 and overlies the switching structure.

Terminals 13 are suitably connected to the switching mechanism, and terminals 19 and 20 are connected by wires 21 and 22 to the synchronous clock motor.

Mounted on a shaft driven by the clock motor so as to rotate once in 24 hours is a mounting disc 23 having a dial front 25. On the edge of the mounting disc 23 are suitable actuating dogs 26 and 27 for effecting timed shifting of the switch mechanism back and forth between its two positions. A time reset knob 41 is provided which extends through an opening in the cover and which is provided with a slot for permitting the dial to be set for time without removing the cover.

The mounting disc 23 rotates in a clockwise direction and the dogs 26 and 27 have cam surfaces 28 and 29, which in such rotation of the mounting disc 23, engage and actuate a follower member 30 through a cam follower 33. The follower member 30 is connected to an actuating lever in the form of a bell crank 31 so as to move the bell crank 31 about its pivot 32 when the follower member 30 is actuated by the cam surfaces 28 or 29. The resulting movement of the bell crank 31 moves the switching mechanism from one of its positions to the other. The operative connection between the cam follower 33 and the bell crank 31 comprises a resilient arm 34 which carries the cam follower 33 on one of its ends and is fastened at its other end to the remote end of the bell crank 31.

The present invention is embodied in a manual switch actuator mechanism shown in detail in Fig. 2. In Fig. 2 mounted on the front of the casing box is the pivot pin 35, serving as a pivot for the movable member 36. The movable member 36 has attached to one end an ear 37 which extends through an opening 38 in the front of the casing box 11. A U-shaped bracket 39 is rigidly fastened to the movable member 36 near its other end. Attached to the remote end of the bell crank 31 is a bracket 40 having a projecting portion 41. The legs 42 and 43 of the bracket 39

are so proportioned as to engage the projection 41 whenever the movable member 36 is moved about its pivot 35, as by manually moving the ear 37 up or down. A resilient spring member 44 is fastened to the pivot pin 35 and a rearwardly extending portion 45 of the movable member 36. This spring member 44 tends to bias the movable member 36 and the bracket 39 to a neutral position. In this neutral position, the legs 42 and 43 of the bracket 39 are separated from the projecting portion 41, and do not interfere with movement of the bell crank 31 during the normal clock actuated sequence of operation.

Openings 46 and 48 are provided in the front of the casing box allowing visual checking and resetting of the timing clock respectively. The casing box is fastened to the base by means of a screw threaded lug 49 attached to the terminal mounting base 50. This threaded lug receives a mounting screw 51 which serves to hold the casing box 11 to the base 10.

In operation, if a setting of the switch mechanism other than that given it by the actuating dog 26 or 27 is desired, the movable member is moved about its pivot 35 by manually moving the ear 37. The resulting movement of the movable member 36 causes one of the legs of the bracket 39 to contact the extension 41 resulting in movement of the bell crank 31 and shifting of the switch mechanism to its other position. As soon as the ear 37 is released, the spring member 44 causes the movable member 36 to return to a neutral position where the bracket 39 is out of contact with the extension 41. This leaves the bell crank 31 unobstructed, allowing the switching mechanism to be shifted to a new position by the actuating dog 26 or 27.

I have herein shown and described certain embodiments of my invention for the purpose of explaining its principles and showing its application. Numerous modifications may be made without departing from the principles of the invention which are included in the following claims.

What I claim is:

1. In a timing device comprising a timing motor, a control device and a casing member partially enclosing said motor and said control device, said control device comprising a pivotally mounted actuating lever and a switch structure actuated by movement of said lever, operating means actuated by said timing motor for moving said lever, manual means providing for manual movement of said lever independently of said operating means, said manual means comprising an elongated movable member pivotally mounted intermediate its ends to the inner face of said casing member and extending substantially parallel to said lever, one free end of said movable member carrying connecting means providing a lost motion connection between said movable member and said lever for moving said lever to actuate said switch structure, resilient means urging said movable member into a normal position wherein said lever may be freely moved by said operating means, the other free end of said movable member having a part extending through an opening in said casing member to provide for manual movement of said movable member to a position wherein said lever is moved through said lost motion connection to actuate said switch structure, said resilient means returning said movable member from said last named position to said normal position without moving said lever to de-actuate said switch structure.

lel to said lever, one free end of said movable member carrying connecting means providing a lost motion connection between said movable member and said lever for moving said lever to actuate said switch structure, resilient means urging said movable member into a normal position wherein said lever may be freely moved by said operating means, the other free end of said movable member having a part extending through an opening in said casing member to provide for manual movement of said movable member to a position wherein said lever is moved through said lost motion connection to actuate said switch structure, said resilient means returning said movable member from said last named position to said normal position without moving said lever to de-actuate said switch structure.

2. In a timing device comprising a timing motor, a control device and a casing member partially enclosing said motor and said control device, said control device comprising a pivotally mounted actuating lever and a switch structure actuated by movement of said lever, operating means actuated by said timing motor for moving said lever, manual means providing for manual movement of said lever independently of said operating means, said manual means comprising an elongated movable member pivotally mounted intermediate its ends to the inner face of said casing member and extending substantially parallel to said lever, one free end of said movable member carrying a bracket comprising spaced legs embracing a portion of said lever, resilient means urging said movable member into a normal position wherein said lever may be freely moved within said legs by said operating means, the other free end of said movable member having a part extending through an opening in said casing member, to provide for manual movement of said movable member to a position wherein said lever is moved by said legs to actuate said switch structure, said resilient means returning said movable member from said last named position to said normal position without moving said lever to de-actuate said switch structure.

ARTHUR F. GEISEL.
